UNITED STATES PATENT OFFICE.

WILLARD F. RICHARDS, OF DEPEW, NEW YORK, ASSIGNOR TO GOULD COUPLER COMPANY, OF NEW YORK, N. Y.

CENTERING AND SUPPORTING DEVICE FOR CAR-COUPINGS.

1,189,386.

Specification of Letters Patent.

Patented July 4, 1916.

Application filed December 29, 1913. Serial No. 809,182.

To all whom it may concern:

Be it known that I, WILLARD F. RICHARDS, a citizen of the United States, residing at Depew, in the county of Erie and State of New York, have invented a new and useful Improvement in Centering and Supporting Devices for Car-Couplings, of which the following is a specification.

This invention relates to centering and supporting devices for railway passenger couplers and other couplers which are provided with a relatively long shank or drawbar pivoted so as to permit the coupler to swing horizontally transversely of the car. These centering devices are for the purpose of permitting the couplers to swing sidewise when the cars are rounding curves and for returning the couplers to and yieldingly retaining them normally in their central position.

The objects of the invention are to provide a centering and supporting device of this sort which is of strong, simple, durable and desirable construction, such that a relatively great swing of the drawbar is permitted by the use of comparatively short, small centering springs; also to employ two centering springs both of which act in conjunction to resist the movement of the drawbar in each direction and to return the drawbar, but which do not project and are not moved laterally beyond the ends of the drawbar support or carry iron; also to construct the device so that the springs are inclosed and protected; and also to improve the construction of devices of this sort in the respects herein-after described and set forth in the claims.

In the accompanying drawings: Figure 1 is a plan view of a coupler and supporting and centering device therefor embodying the invention. Fig. 2 is a similar view showing the coupler swung to one side. Fig. 3 is a transverse sectional elevation thereof, on an enlarged scale, in line 3—3, Fig. 1. Fig. 4 is a transverse sectional elevation thereof, on an enlarged scale, in line 4—4, Fig. 2. Fig. 5 is a horizontal section thereof, partly in plan, on a still larger scale, in line 5—5, Fig. 3. Figs. 6 and 7 are fragmentary cross sectional elevations thereof on line 6—6 and 7—7, respectively, Fig. 3. Fig. 8 is a fragmentary end view of the carry-iron.

A represents a coupler and a the shank or

drawbar thereof, which is pivoted at its inner end at a' to permit the coupler to swing sidewise to either side of the normal central position shown in Fig. 1. The coupler and drawbar may be of any usual or desired construction and may be pivoted to the car or other railway rolling stock in any suitable manner.

B represents a carry-iron or support for the outer end of the drawbar. This carry-iron, as usual, has upright end attaching portions b with laterally projecting upper ends adapted to be bolted or otherwise secured to the car or other rolling stock, and a horizontal portion b' which connects the lower ends of the attaching portions beneath the drawbar, which is supported thereby. The carry-iron B preferably consists of a single-piece steel casting, the connecting portion of which is in the form of an open-ended cylinder or tubular spring housing having a substantially flat horizontal top face b².

C represents a saddle or slide in which the drawbar rests and which is adapted to slide with the drawbar on the carry-iron B between the attaching portions b thereof. This saddle preferably consists of a single-piece substantially U-shaped steel casting having a horizontal bottom and upwardly projecting sides c between which the drawbar is confined, said sides c having convexed inner surfaces, as shown in Figs. 1 and 2, on which the drawbar is adapted to rock and slide in the horizontal swinging movements of the drawbar. The saddle has a flat bottom face which rests and is adapted to slide on the flat top face b² of the spring housing b' of the carry-iron and is provided with a central lug D and end lugs d d' which extend downwardly into a longitudinal slot d² in the top of the spring housing b' of the carry-iron.

Within the spring housing b' at opposite sides of the depending central lug D of the saddle are arranged two coil springs E E' which bear at their outer ends against sliding abutments. These sliding abutments are preferably in the form of sockets or sleeves F F' in which the springs are confined. The sleeves are provided at their inner ends with lugs f f' respectively, which extend upwardly into the slot d² in the spring housing. The lugs f f' prevent the

spring sleeves from turning in the spring housing and coöperate with the lugs d d' on the saddle, as hereinafter explained.

The spring and sliding spring sleeves are retained in the spring housing by end caps G which are secured in place on the ends of the housing by a bolt or rod H which extends lengthwise centrally through the spring housing and through the caps G. The slot d^2 in the spring housing is preferably continued through the upright end portions b of the carry-iron, and the caps G have notches g registering with the slot so that any cinders or other matter which may fall into the slot will be shoved out of the open ends thereof by the lugs d d' of the saddle in the operation of the centering device and will not collect in the housing or interfere with the movement of the saddle. The caps can be prevented from turning on the housing so as to retain their notches g in register with the slot d^2 by ribs g' on the caps entering notches in the ends of the housing, or in any other convenient way. The bolt or rod H passes loosely through the spring sleeves and springs and through a hole h in the central lug D of the saddle and thus retains the saddle as well as the other parts in place on the carry-iron. The spring housing is provided internally midway of its length with fixed abutments or ribs I against which the inner ends of the springs are adapted to react. These abutments are spaced apart far enough to allow the lug D of the saddle to pass between them. Washers K are preferably interposed between the inner ends of the springs and the lug D and are adapted to engage the lug and the abutments I. Normally the springs E E' hold the spring sleeves F F' in the outer ends of the spring housing against the caps G and press against the opposite sides of the central lug D of the saddle, thereby holding the saddle and the drawbar in the central position. In this position of the parts the lugs f f' of the spring sleeves bears against the inner sides of the end lugs d d' of the saddle, as shown in Fig. 3. When the drawbar is moved in one direction, for instance to the right, as shown in Fig. 4, the saddle will be correspondingly moved and the central lug D thereof will compress the right-hand spring E'. At the same time the lug d of the saddle, engaging the lug f of the spring sleeve F, will draw this sleeve inwardly and compress the other spring E between the sleeve F and the abutments I. Both springs are thus compressed and both will act to return the saddle and drawbar to the central position when the side pressure on the drawbar is released. In a similar manner, when the drawbar and saddle are moved in the opposite direction from the central position the spring E will be compressed by

the central lug D of the saddle and the spring sleeve F' will be drawn inwardly by the engagement of the lugs d' and f' and will compress the other spring E' against the abutments I. Therefore both springs act to resist the movement of the drawbar in either direction and to return it to the central position, and smaller springs can be used than if one spring only acted in each direction.

By the described construction the carry-iron and the saddle can each be made of a single-piece casting, the springs are inclosed and protected and do not project beyond the ends of the housing and are not moved outwardly beyond the same in the operation of the device and therefore do not interfere with other nearby parts on the car. The spring sleeves close the slot d^2 in the housing and prevent cinders or other matter from getting into the springs and interfering with the operation thereof. The cinders or other matter which may fall into the slot d^2 are shoved out of the open ends thereof by the lugs d d' of the saddle.

I claim as my invention:

1. The combination of a drawbar carry-iron having a hollow horizontal portion which forms a spring housing, a drawbar saddle which is arranged to slide on said housing and has a lug projecting into said housing, springs in said housing at opposite sides of said lug and acting thereon, an abutment in said housing for the inner ends of said springs, sliding abutments in said housing for the outer ends of said springs, and means whereby one of said sliding abutments is moved with said saddle when said saddle is moved in either direction.

2. The combination of a drawbar carry-iron having a hollow horizontal portion which forms a spring housing, a drawbar saddle which is arranged to slide on said housing and has a lug projecting into said housing, springs in said housing at opposite sides of said lug and acting thereon, a stationary abutment in said housing between said springs and against which the inner ends of said springs are adapted to react, sliding sleeves against which the outer ends of the springs act, and lugs on said saddle engaging lugs on said sleeves, whereby both of said springs yieldingly resist the movement of said saddle in both directions.

3. The combination of a drawbar carry-iron, a drawbar saddle which is arranged to slide on said carry-iron, springs arranged at opposite sides of a part of said saddle and acting against said part, a stationary abutment between said springs against which the inner ends of said springs are adapted to react, sliding abutments against which the outer ends of said springs act, and parts on said saddle adapted to engage said slid-

- ing abutments whereby one of said sliding abutments is moved and compresses one of said springs when said saddle is moved in either direction.
5. 4. The combination of a drawbar carry-iron having end attaching portions and a hollow open-ended connecting portion provided with a longitudinal slot extending from end to end thereof, centering means 10 for the drawbar located in said hollow portion and including a part extending through said slot for engagement with the drawbar, and caps for the ends of said hollow portion having slots registering with the ends 15 of said longitudinal slot.
5. The combination of a drawbar carry-iron having a tubular horizontal portion which forms a spring housing and has open ends and a longitudinal slot, a drawbar saddle which is arranged to slide on said housing, abutments arranged to slide in the opposite end portions of said housing, engaging parts on said saddle and said abutments extending through said slot in the 20 housing whereby said abutments are adapted to be moved by said saddle, spring means in said housing for yieldingly resisting the inward movement of said abutments, caps for closing the ends of said 25 housing, abutments and spring means.

housing, and a stationary securing bolt for 30 said caps which extends through said housing, abutments and spring means.

6. The combination of a drawbar carry-iron having a tubular horizontal portion which forms a spring housing and has open 35 ends and a longitudinal slot in its top which is open at the ends of the housing, a drawbar saddle which is arranged to slide on said housing, abutments arranged to slide in the opposite end portions of said housing, engaging parts on said saddle and abutments extending through said slot in the housing whereby said abutments are adapted 40 to be moved by said saddle, spring means in said housing for yieldingly resisting the inward movement of said abutments, caps for closing the ends of said 45 housing, said caps leaving the ends of said slot open, and a stationary securing bolt for said caps which extends through said 50 housing, abutments and spring means.
